UNITED STATES PATENT OFFICE.

THOMAS S. JOHNSON, OF SCRANTON, PENNSYLVANIA.

GRATE-BAR.

1,125,551.

Specification of Letters Patent.

Patented Jan. 19, 1915.

Application filed April 7, 1913. Serial No. 759,560.

To all whom it may concern:

Be it known that I, THOMAS S. JOHNSON, a citizen of the United States, residing at Scranton, in the county of Lackawanna and 5 State of Pennsylvania, have invented new and useful Improvements in Grate-Bars, of which the following is a specification.

This invention relates to certain new and useful improvements in grate bars, and pertains more particularly to a grate bar which 10 has means incorporated therein to convey air to the fuel throughout the entire area of the bar.

Further the invention aims to provide a 15 grate bar structure in which means is provided for preventing the ashes from interfering with proper alinement of the grate bars, where the latter overlap.

In the drawings: Figure 1 is a fragmentary end elevation partly in section, showing the overlapping portions of the grate bars; Fig. 2 is an enlarged top plan view of one 20 of the grate bars; and Fig. 3 is a side elevation of Fig. 2.

The upper face of each grate bar 1 is 25 formed with a series of intersecting grooves 3, which latter are preferably diagonally arranged, and cover the entire area of the grate bar with a series, or network, so to speak, of horizontal air passages, which underlying the fuel, will allow access of the air to the latter, throughout substantially the entire area of the grate bar. In order 30 to supply air to the horizontal air passages 3, the grate bars are formed with a series 35 of vertical openings 4 that provide vertical air passages to supply air to the horizontal air passages 3. The vertical air passages 4 are formed at the intersections of the horizontal air passages 3, in order to enable each 40 vertical air passage 4 to supply air to four of the horizontal air passages 3, which results not only in even distribution of the air to the fuel, but also in quick distribution 45 as well. The longitudinal sides of the grate bars are also formed with vertical grooves 5 that feed the air to the outer ends of the grooves 3 where the latter intersect.

One end of each grate bar has a ledge 6 50 that is engaged on its upper face by the adjacent end 7 of the adjacent grate bar, the ledge 6 being located in a plane below the plane of the end 7 and being formed with a series of vertical openings 8, which 55 latter register with the lower ends of pas-

sages 9 that are formed between the adjacent ends of adjacent grate bars, in order to allow ashes to gravitate down through the passages 9, and then through the passages 6 so as not to interfere with proper 60 alinement between the grate bars where same contact at their ends, such as frequently occurs where the ashes are permitted to accumulate on the ledges 6. In addition the passages 8 and 9 further act to 65 supply air to the fuel.

The passages 3 and 4, may be formed of any depth or width to meet different conditions of use or character of the fuel.

What is claimed is:

1. A pair of grate bars having their adjacent ends similarly inclined and arranged in substantial parallelism to conjointly form a passage diagonally related to the top and bottom faces of the grate bars, and a horizontally disposed ledge on the end of one of said grate bars which ledge has its upper face extending across said diagonal passage and engaged with the under face of the end of the other grate bar, said ledge 70 being formed with a plurality of vertical openings which register with said diagonal passage so as to allow air to be fed through said openings and through the diagonal passage to have access to the upper faces of 75 the grate bars, and to also allow ashes which contact with the ledge to gravitate down through said openings.

2. A pair of grate bars having their adjacent ends spaced to form a passage there- 90 between, a horizontal ledge on the end of one of said grate bars which ledge has its upper face extending across said passage and engaged with the under face of the other grate bar, said ledge being formed 95 with vertical openings which register with said passage and said bars having horizontal grooves on their upper faces which communicate directly with said passage whereby air which enters the openings will enter 100 the passage and be distributed to said horizontal grooves.

In testimony whereof I have hereunto set my hand in presence of two subscribing witnesses.

THOMAS S. JOHNSON.

Witnesses:

D. E. ROSSER,
JOSEPH ROWAN.
